Term of patent 14 years

(Cl. D83—1)

F I G. 1

FIG. 2

FIG. 1 is a front perspective view of a recorder for monitoring body functions showing my new design with the door closed, and

FIG. 2 is a front perspective view similar to that of FIG. 1 but showing the door open.

The opposite side, not shown, is substantially a mirror image of the side shown, and the rear, not shown, is substantially plain.

The fragmentary portion of the cord shown in FIGS. 1 and 2 is broken away for convenience of illustration only.

The members shaded in black on the drawings represent contrasting color.

I claim:

The ornamental design for a recorder for monitoring body functions, substantially as shown and described.
